CLAIM

The ornamental design for a flexible beverage container, as shown and described.

DESCRIPTION

FIG. 1 is a front perspective view of a flexible beverage container.

FIG. 2 is a top view thereof.

FIG. 3 is a bottom view thereof.

FIG. 4 is a front elevational view thereof.

FIG. 5 is a right side elevational view thereof, the left side is identical and therefore not required; and,

FIG. 6 is a rear elevational view thereof.
